UNITED STATES PATENT OFFICE.

CHARLES H. IVES, OF LITTLE FALLS, NEW YORK.

CAR-DOOR LOCK.

SPECIFICATION forming part of Letters Patent No. 460,798, dated October 6, 1891.

Application filed January 28, 1891. Serial No. 379,396. (No model.)

To all whom it may concern:

Be it known that I, CHARLES H. IVES, a citizen of the United States of America, residing at Little Falls, in the county of Herkimer and State of New York, have invented certain new and useful Improvements in Freight-Car-Door Locks, of which the following is a specification, reference being had therein to the accompanying drawings.

10 My invention relates to improvements in car-door locks, and is especially designed for employment upon cars having sliding doors, such as freight-cars.

15 The leading object of my invention is the provision of a lock for the purpose named which will prevent thieves or others from unlawfully entering the cars while they are in motion or when stopped. The locks at present used upon the cars are defective for the purpose, in that persons can while the cars are in motion tamper with the lock and release the same and enter the cars; but my lock will prevent entrance to the cars by unlawful methods.

20 A further object of my invention is the provision of a lock of the character and for the purpose mentioned which can be applied to freight-cars at a small expense, which will be of durable construction, and easy and effective of operation.

25 To attain the desired objects the invention consists of a locking lever or levers and tumbling or locking rods disposed beneath the cars, whereby they cannot be tampered with.

30 The invention further consists of locking rods journaled to the bottom of the car and having the outer end adapted to engage and lock the doors and their inner ends secured by a lever or levers, and means for securing said lever or levers.

35 40 The invention further consists in certain features of construction and combinations of parts, whereby an efficient and useful lock is provided, substantially as herein illustrated, described, and then specifically defined and distinguished by the claims.

45 In order that the construction, operation, and advantages of my improved lock may be readily understood, I have illustrated the same in the accompanying drawings, in 50 which—

Figure 1 represents a plan view of the bottom of a car with my improved lock applied.

Fig. 2 represents an elevation of a car with my lock applied, the parts being in the position they assume when locked. Fig. 3 represents a similar view, the parts being in the position they assume when open or unlocked. Figs. 4 to 9 represent detail views of the parts of the lock.

55 Referring by numerals to the drawings, in which similar numerals denote corresponding parts in the several views, the numeral 1 denotes the car, or as much thereof as is necessary to illustrate the application of my lock, having the usual sliding doors 2, which ride 60 on the brackets 3, all of which are of the well-known or of any desired construction. On the bottom of the car are the longitudinal parallel bars or rails 4, in the two central ones of which is mounted a shaft or pin 5, bearings 65 therefor being secured to said rails, and on this pin or shaft is mounted a locking-lever 6.

70 I would here state that I show and prefer to use but one of the locking-levers, as one performs the functions in a perfect manner 75 and is less expensive than using two, although I may use two if I desire. This lever is curved at the pivotal end and is made large at the free end—that is, the free end is weighted—whereby the lever is normally held down, 80 the purpose of which will appear. If it is desired to lock the lever down, I employ a bar or arm 7, which passes through an opening in the plate 8 and is secured by a suitable lock 9, preferably a padlock. The lever 85 is also provided with the recesses 10—one on each side—and the depression 11 for a purpose to be explained. The recesses or kerfs 10 are arranged one on each side of the lever, and are inclined inward, as shown, and the 90 groove or depression 11 is arranged transversely on the under face of the lever.

95 In the rails on the bottom of the car are journaled the tumbling-rods 12, the inner ends of which are formed with the crank 13, having the toe 14, and the outer ends of the rods are provided with the toe or locking projection 15, which is adapted when the doors are closed to be drawn outwardly and through the plate or keeper 16, secured to the doors 100 of the car, the doors being formed with kerfs 17 to admit the toe, and said toe being beveled or smoothed to press firmly against the keeper-plate on the car-doors to securely lock

said doors. When the doors are locked, the cranks have the toe thereon resting in the transverse groove or depression 11 of the lever, and the toe on the outer ends of the rods 5 is in engagement with the keeper-plates on the car-doors, as seen in Figs. 1 and 2, and when the doors are unlocked the toes on the cranks rest in the recesses or kerfs 10 of the lever and the toes on the outer ends of the 10 rods are out of engagement with the keeper-plate.

When it is desired to secure the car, the doors are closed, the rods are turned by inserting a key 18 into an opening in the outer 15 ends of the rods, which causes the toes on the outer ends of the rods to engage the locking-plate on the car-door and the cranks on the inner ends of the rods to rest in the transverse groove or depression 11 in the lever, 20 thus securing the rods and locking the doors, and the weight of the lever holds the rods in locked position, or the lever may be locked down; and to unlock the doors it is only necessary to turn the rods in the reverse direction, 25 which releases the toes on the outer ends of the rods. Then push the rods inward, which causes the toes on the inner ends to rest in the recesses 10 of the lever, as shown by dotted lines in Fig. 1. It will thus be seen that by turning the rods in one direction the toes 14 thereof are caused to enter the groove 11 of the lever, which causes the locking projections 15 to engage the keeper 16, and the weight of the lever holds the rods in this position, thus locking the doors; and when the 30 rods are turned in the opposite direction the projections 15 are released from the keepers 16 and the cranks 13 are brought opposite the inclined recesses or kerfs 10 of the lever, 35 and it is then only necessary to push the rods inward and force the cranks 13 into the recesses 10, which moves the outer ends of the rods out of the path of the doors, allowing said doors to be opened, as is evident.

From the foregoing it will be seen that the 45 lock is operated by turning the rods in opposite directions and that the lock is easy and efficient in operation, is of simple and inexpensive construction, and can be easily applied to cars.

Having fully described my invention, I claim—

1. In a car-door lock, the combination, with the car and the doors thereof, of a lever pivoted at one end to the under side of the car, and 55 rods rotatably mounted in the car and having cranks on their inner ends, formed with toes for engaging the other end of said lever, and toes on their outer ends for engaging the door-keepers, substantially as and for the purpose 60 described.

2. In a car-door lock, the combination, with the car and the doors thereof provided with openings and keepers at the lower edges, of a lever pivoted to the under side of the car and 65 having a transverse groove and recesses, as described, rods pivoted in the car and having toes for engaging the groove, and cranks for engaging the recesses of the lever and at their outer ends provided with toes for engaging 70 the keepers on the car-doors, substantially as described.

3. In a car-door lock, the combination, with the car and the doors having keepers, of the weighted lever pivoted to the under side of 75 the car and having the groove and recesses, as described, the rods pivoted to the car and having their inner ends adapted to engage the groove and recesses of the lever and their outer ends adapted to engage the keepers on the 80 doors, and a lock for securing the lever, substantially as described.

In testimony whereof I affix my signature in presence of two witnesses.

CHARLES H. IVES.
